UNITED STATES PATENT OFFICE

109,393

DESIGN FOR AN EDUCATIONAL MODEL

Eleanor W. Dodd, Washington, D. C.

Application December 22, 1937, Serial No. 73,806

Term of patent 3½ years

To all whom it may concern:

Be it known that I, Eleanor W. Dodd, a citizen of the United States, residing at Washington, in the District of Columbia, have invented a new, original, and ornamental Design for an Educational Model, of which the following is a specification, reference being had to the accompanying drawing forming a part thereof.

I claim:

The ornamental design for an educational model, substantially as shown.

ELEANOR W. DODD.
